UNITED STATES PATENT OFFICE

2,084,103

DOUBLE WINDOW CONSTRUCTION

Robert A. Miller, Tarentum, Pa., assignor to Pittsburgh Plate Glass Company, Allegheny County, Pa., a corporation of Pennsylvania

Application October 5, 1935, Serial No. 43,726

2 Claims. (Cl. 20—56.5)

The invention relates to double glazed windows and particularly to the frame construction of the unit which protects the margins of the pairs of sheets and holds the sheets in assembled relation with suitable compression upon the spacers at the edges of the sheets which provide the seal for the space between the sheets. One object of the invention is the provision of a frame which may be made from relatively light sheet metal of inexpensive construction, which has at the same time a substantial degree of rigidity in its base portion, so that buckling or bending at this point is avoided when the unit is installed and its edges placed under compression, such as occurs in car windows. A further object of the invention is the provision of improved means for locking the two angle members which make up the channel frame together so that no additional fastening means, such as screws or wedges are required for holding the parts in assembled relation. This feature reduces the material cost and the labor cost in assembling and disassembling as compared with units which lack this feature. One embodiment of the invention is shown in the accompanying drawing, wherein:

Figure 1 is a front elevation of the complete unit. And Fig. 2 is an enlarged section on the line II—II of Fig. 1.

Referring to the drawing, 1 and 2 are glass sheets of the same size; and 3 is a spacer of yielding material, preferably rubber, which is placed under compression by the frame and acts as a seal. The frame, which is made in four sections, one for each side of the unit, is of channel form and is made up of a pair of oppositely facing angles 4 and 5, having the flanges 6 and 7 in opposition to the outer faces of the glass sheets, sealing material in the form of the strips 8 being interposed between the flanges and the faces of the sheets. The angles are formed of thin sheet metal, such as steel which are readily bent to the desired configurations.

The base of the angle 4 is made up of three parallel folds or strips 9, 10 and 11 with the folds 10 and 11 spaced apart to provide a receiving slot for the base of the angle 5. The base 12 of the angle 5 fits snugly into the slot between the folds 10 and 11 and is provided at its juncture with the flange 7 with a shoulder 13. This shoulder 13 interlocks with a shoulder 14 formed at the end of the base of the angle 4, as shown in Fig. 2. The interlock at this point occurs with a snap action due to the spring in the metal, so that after the parts are assembled, they are securely, but releasably, held in interlocking relation. This permits of the ready disassembling of the unit, should this be required, in case one of the glass sheets is broken. The parts of the frame, as above described, are so proportioned that when the angles 4 and 5 are snapped into

assembled relation, the spacer 3 and the strips 8, 9 are placed under compression, thus insuring a good seal. The frame, as thus constructed, has relatively yielding spring flanges, and at the same time has a relatively stiff, rigid base portion. This is of advantage when the unit is clamped in a car frame in which considerable pressure is applied on the edge of the unit, such pressure tending to bend or buckle the base of the channel frame and to spring the flanges outward. With the present construction, this difficulty is overcome. Other advantages incident to the construction will be readily apparent to those skilled in the art.

It will be understood that the frame construction on each side of the unit is similar and that the frame members come together along the lines 15, as shown in Fig. 1, where they are either soldered or secured together by any suitable holding means.

What I claim is:

1. In combination in a double window construction, a unit comprising a pair of glass sheets with a yielding spacer between the margins thereof, and a frame made up of channels each comprising a pair of angles of sheet metal construction having their flanges in opposition to the outer faces of the glass sheets and their bases overlapping and provided with projecting portions which snap into interlocking relation and hold the angles in assembled relation when the frame is applied to the glass sheets and the spacer is placed under compression, one of said bases consisting of three parallel folds of metal with a slot between two of such folds, and the other of said bases consisting of a strip which fits snugly into said slot throughout its length so that the base of the unit is made up of four layers of metal, each of which contacts with the layer next adjacent thereto.

2. In combination in a double window construction, a unit comprising a pair of glass sheets with a yielding spacer between the margins thereof, and a frame made up of channels each comprising a pair of angles of sheet metal construction having their flanges in opposition to the outer faces of the glass sheets and their bases overlapping and provided with a shoulder and recess interlock which snap into locking engagement when the angles are applied to the glass sheets in interfitting relation and the spacer is placed under compression, one of said bases consisting of three layers of metal folded one upon the other in parallelism with a slot between the two inner layers, and the other of said bases consisting of a strip which fits snugly in said slot throughout its length so that the base of the unit is made up of four layers of metal, each of which contacts with the layer next adjacent thereto.

ROBERT A. MILLER.
